WINDING AND SETTING MECHANISM FOR
WATCH AND CLOCK MOVEMENTS AND
THE LIKEHeinrich Stamm, Grenchen, Switzerland, assignor
to ETA AG., Ebauches-Fabrik, Grenchen, Switzerland, a joint-stock company of SwitzerlandApplication March 24, 1949, Serial No. 83,224
In Switzerland March 30, 1948

4 Claims. (Cl. 58—69)

1

This invention relates to winding and setting mechanisms for watch and clock movements and the like, which comprise a rocking setting member.

In hitherto used movements having mechanisms of the kind referred to, the intermediate wheels carried by the rocking setting member lay on the side of the latter turned away from the dial, i. e., seen from the dial, these wheels lay below the rocking setting member. In these prior mechanisms, assembling the rocking setting member and the intermediate wheels was very troublesome in that the latter were liable to drop out, and in that there was no means by which to attach the wheels to the setting member during assembling.

It has proved advantageous and it is an object of my invention to leave the usual way, and to mount the intermediate wheels of the rocking setting member on the side turned towards the dial, where they are held by a cover plate constituted by the base of the setting lever spring.

Other objects and features will be apparent as the following description proceeds, reference being had to the accompanying drawing showing, by way of example, one embodiment of the invention, and wherein

Fig. 1 is a section through the axis of the rocking-bar, and

Fig. 2 is a top view of the parts of the winding and setting mechanism, which are necessary for the comprehension of the invention.

The rocking-bar 3 is pivotally mounted on a tubular portion 2 of the plate 1, and possesses two pins 4 and 5 projecting from the face of the rocking-bar 3 which is turned away from the plate 1. The outer intermediate wheels 6 and 7 are loosely mounted on these pins 4 and 5, and mesh with a center intermediate wheel 8 loosely mounted on a tubular portion 9 of the rocking-bar 3. Therefore, seen from the dial (not shown), the rocking-bar 3 lies below the intermediate wheels 6 and 7. These wheels are prevented from dropping out by the base 10 of the setting lever spring. A spring arm 11 integral with said base 10 is provided with the two cutouts 24 and 25 which cooperate with the pin 23 projecting from one end of an arm of the setting lever 12. The two-armed setting lever is pivotally mounted on the plate 1 and the end of the arm carrying the pin 23 is shaped in the form of a nose 20 which may cooperate with a notch 21 provided in the edge of the rocking-bar 3. The other arm of the setting lever carries a pin 19 projecting therefrom and extend-

2

ing into an annular slot 22 of the stem 18 which may be axially shifted in the plate 1. The stem drives a winding pinion 26 which is constantly in gear with the center intermediate wheel 8.

5 The base 10 of the setting lever spring is fixed to the plate 1 by means of a screw 13 screwed into a central bore of the tubular portion 2 around which the rocking-bar 3 rotates. The setting lever spring is kept against rotation 10 around the screw 13 by a projecting arm maintained in a recess of the plate both the arm and the recess being not shown in the drawing. An aperture 17 is provided in the base 10 of the setting lever spring and the pin 4 projecting from the rocking-bar 3 arises through this aperture 15 to cooperate therewith.

The rocking-bar spring 15 is situated in a recess 14 of the plate 1, and cooperates with a pin 16 of the rocking-bar 3, room being left in the plate 1 to allow movement of the pin 16.

As may be seen, the axial play of the intermediate wheels mounted on the rocking bar 3 is limited by a stationary cover plate constituted by the base 10.

25 The mechanism described above is destined to work in two positions, namely the winding position and the setting position (shown in Fig. 2).

These positions will be changed one into the other by shifting manually the stem 16 into or out of the plate 1.

30 The setting position of this mechanism shown in Fig. 2 may consequently be changed into the winding position by pushing the stem 18 into the plate 1. Because of the cooperation of the pin 35 19 and the annular slot 22, the setting lever pivots counterclockwise until its pin 23 comes into the cutout 25 of the spring arm 11. The nose 20 releases then the rocking-bar 3 and the rocking-bar spring 15 bearing against the pin 16 pushes said pin and rotates the rocking-bar 3 40 counterclockwise, until its pin 4 leans against the edge of the aperture 17.

In this position, the intermediate wheel 7 is free and the intermediate wheel 6 is in mesh with a winding wheel which is not shown.

45 The pin 4 and the aperture 17 are so disposed as to prevent the intermediate wheel 6 and said winding wheel from coming to near what could cause a clamping of the mechanism.

50 The mechanism is returned from that winding position to the setting position shown in Fig. 2 by pulling the stem 18 out of the plate 1.

The annular slot 22 drives the pin 19 of the setting lever 12 which consequently rotates clockwise until its pin 23 comes into the cutout 24

of the spring arm 11 of the setting lever spring.

During the movement of the setting lever, its nose 20 bears against the rocking-bar and rotates it clockwise against the power of the rocking-bar spring 15 until the nose 20 of the setting lever 12 catches the notch 21 of the rocking-bar 3 and clamps with it so as to prevent a further displacement of the rocking bar.

In this position the intermediate wheel 6 is free and the intermediate wheel 7 is in mesh 10 with a setting wheel which is not shown.

The nose 20 and the notch 21 are so disposed that the intermediate wheel 7 and said setting wheel stay at the appropriate distance for a normal gearing. Mechanically speaking, this new arrangement is superior to the one used in the prior art. Furthermore, the novel arrangement facilitates the assembling of the rocking-bar with its intermediate wheels. The rocking-bar and the intermediate wheels may be assembled piece by piece. Moreover, mounting the rocking-bar spring below the rocking-bar is possible, which results in very favorable conditions as to utilization of the space available.

While I have described and illustrated one embodiment of my invention, I do not wish to unnecessarily limit the scope of my invention, but reserve the right to make such modifications and rearrangements of the several parts as may come within the purview of the accompanying claims.

What I claim is:

1. In a watch or clock movement, a plate, and a winding and setting mechanism comprising a rocking-bar pivotally mounted on said plate and having a notch and a projection, said projection extending on the side opposite said plate, a two-armed setting lever pivotally mounted on said plate and having a nose and two projections, one at each end of said arms, said setting lever moving said rocking-bar, an axially movable stem having an annular slot for moving said setting lever, three intermediate wheels rotatably mounted on said rocking-bar on the side thereof opposite said plate, said three wheels lying in one plane, and a setting lever spring having a spring arm with two cutouts and a base having an aperture and being detachably secured to said plate and positioned on the side of said wheels opposite the rocking-bar and serving as a cover to retain said intermediate wheels on the rocking-bar against axial movement, one of said projections of said setting lever cooperating with said annular slot of said stem and the other of said projections of said setting lever cooperating with said two cutouts of said spring arm, said nose of said setting lever cooperating with said notch of said rocking-bar and said projection of the rocking-bar extending on the side opposite said plate arising through said aperture of said base and cooperating with said aperture, for accurately determining both the setting and the winding positions of said rocking-bar.

2. In a watch or clock movement, a plate, and a winding and setting mechanism comprising a rocking-bar pivotally mounted on said plate and having a notch and a projection, said projection extending on the side opposite said plate, a two-armed setting lever pivotally mounted on said plate and having a nose and two projections, one at each end of said arms, said setting lever moving said rocking-bar, an axially movable stem having an annular slot for moving said setting lever, three intermediate wheels rotatably mounted on said rocking-bar on the side thereof

opposite said plate, said three wheels lying in one plane, said projection of the rocking-bar extending on the side opposite said plate being the axle of an outer of said intermediate wheels, and a setting lever spring having a spring arm with two cutouts and a base having an aperture and being detachably secured to said plate and positioned on the side of said wheels opposite the rocking-bar and serving as a cover to retain said intermediate wheels on the rocking-bar against axial movement, one of said projections of said setting lever cooperating with said annular slot of said stem and the other of said projections of said setting lever cooperating with said two cutouts of said spring arm, said nose of said setting lever cooperating with said notch of said rocking-bar and said projection of the rocking-bar extending on the side opposite said plate arising through said aperture of said base and cooperating with said aperture, for accurately determining both the setting and the winding positions of said rocking-bar.

3. In a watch or clock movement, a plate having a tubular portion, and a winding and setting mechanism comprising a rocking-bar pivotally mounted on said tubular portion of said plate and having a notch and a projection, said projection extending on the side opposite said plate, a two-armed setting lever pivotally mounted on said plate and having a nose and two projections, one at each end of said arms, said setting lever moving said rocking-bar, an axially movable stem having an annular slot for moving said setting lever, three intermediate wheels rotatably mounted on said rocking-bar on the side thereof opposite said plate, said three wheels lying in one plane, said projection of the rocking-bar extending on the side opposite said plate being the axle of an outer of said intermediate wheels, and a setting lever spring having a spring arm with two cutouts and a base having an aperture and being detachably secured to said plate by a screw screwed on said tubular portion of said plate, and positioned on the side of said wheels opposite the rocking-bar and serving as a cover to retain said intermediate wheels on the rocking-bar against axial movement, one of said projections of said setting lever cooperating with said annular slot of said stem and the other of said projections of said setting lever cooperating with said two cutouts of said spring arm, said nose of said setting lever cooperating with said notch of said rocking-bar and said projection of the rocking-bar extending on the side opposite said plate arising through said aperture of said base and cooperating with said aperture, for accurately determining both the setting and the winding positions of said rocking-bar.

4. In a watch or clock movement, a plate having a recess and a tubular portion, and a winding and setting mechanism comprising a rocking-bar pivotally mounted on said tubular portion of said plate and having a notch, a projection extending on the side opposite said plate and a projection extending towards said plate, a rocking-bar spring positioned between said rocking-bar and said plate in said recess of said plate and bearing against said projection of said rocking-bar, extending towards said plate, a two-armed setting lever pivotally mounted on said plate and having a nose and two projections, one at each end of said arms, said setting lever moving said rocking-bar, an axially movable stem having an annular slot for moving said setting lever, three intermediate wheels rotatably mounted on said

rocking-bar on the side thereof opposite said plate, said three wheels lying in one plane, said projection of the rocking-bar extending on the side opposite said plate being the axle of an outer of said intermediate wheels, and a setting lever spring having a spring arm with two cutouts and a base having an aperture and being detachably secured to said plate by a screw screwed on said tubular portion of said plate, and positioned on the side of said wheels opposite the rocking-bar and serving as a cover to retain said intermediate wheels on the rocking-bar against axial movement, one of said projections of said setting lever cooperating with said annular slot of said stem and the other of said projections of said setting lever cooperating with said two cutouts of said spring arm, said nose of said setting lever co-operating with said notch of said rocking-bar and

said projection of the rocking-bar extending on the side opposite said plate arising through said aperture of said base and cooperating with said aperture, for accurately determining both the setting and the winding positions of said rocking-bar.
